UNITED STATES PATENT OFFICE.

OREN W. KINLEY, OF DES MOINES, IOWA.

SPARK-GAP.

1,342,816.

Specification of Letters Patent. Patented June 8, 1920.

Application filed July 8, 1919. Serial No. 309,492.

To all whom it may concern:

Be it known that I, OREN W. KINLEY, a citizen of the United States, and resident of Des Moines, in the county of Polk and State 5 of Iowa, have invented a certain new and useful Spark-Gap, of which the following is a specification.

My invention relates to that class of spark gaps that are usually employed in 10 connection with internal combustion engines and are interposed between the spark plugs of the engine and the service wires running to the spark plugs, for the purpose of visually detecting short circuits and for 15 increasing the intensity of the spark in the spark plugs.

The object of my invention is to provide a spark gap of this class of simple, durable and inexpensive construction, in which all 20 of the parts may be constructed easily and inexpensively of cheap materials, and readily and easily assembled without the use of screw-threaded parts, and when so assembled will provide a spark gap device 25 in which the parts cannot be moved from their proper position of adjustment relative to each other; and furthermore, to provide a spark gap of this class in which the spark within the spark gap device is visible to 30 the operator at all times and yet is protected in such a manner as to prevent igniting any gases that may be present adjacent to the spark plug, and also prevent dust, etc., from entering the space between the 35 terminals forming the spark gap.

My invention consists in the construction, arrangement and combination of the various parts of the device, whereby the objects contemplated are attained, as hereinafter more fully set forth, pointed out in 40 my claims, and illustrated in the accompanying drawings, in which:

Figure 1 shows a spark plug of ordinary construction, and a conductor leading there- 45 to, with one of my improved spark gaps connected to the conductor and spark plug.

Fig. 2 shows a longitudinal sectional view of a spark gap embodying my invention and attached to a conductor wire.

Fig. 3 shows a top or plan view of same.

Fig. 4 shows a vertical, longitudinal, sec- 50 tional view of a modified form of same.

Fig. 5 shows a plan view of the central insulating member of the spark gap shown in Fig. 4. 55

Fig. 6 shows a plan view of the lower insulating member of same.

Fig. 7 shows a plan view of the mica member of same; and

Fig. 8 shows a plan view of the top insulating member of same. 60

Referring to the accompanying drawings, I have used the reference numeral 10 to indicate a spark plug of ordinary construction, and 11 a wire for conducting 65 current to the spark plug. This wire is preferably provided at one end with a flattened conducting member 12, having a circular opening therein to receive a rivet for connecting it to the spark plug. 70

In the form of my invention shown in Figs. 4 to 8 inclusive, the spark gap device is composed of a lower insulating member 13 shown in Fig. 6, and provided with two circular openings 14. Immediately above 75 the bottom member 13 is a second insulating member 15 having formed therein two circular recesses designed to receive and fit around the disk-shaped spark gap terminals 16. These terminals are made of brass or 80 other good electrical conducting material, and are provided with central openings to receive hollow rivets hereinafter described. They are so arranged within the insulating member 15 that their adjacent edges stand 85 spaced apart from each other the proper distance for providing an air space of considerable length to form a spark from one of the terminals 16 to the other through the air space when an electric current of 90 proper intensity is passed through said terminals.

Directly above the insulating member 15 and the terminal 16 is a mica plate 17 having two openings 18 therein to receive the 95 hollow rivets. Immediately above the mica member 17 is a third insulating member 19 having rivet openings 20 therein, and an opening 21 between them through which the spark may be observed. 100

In assembling the device the parts are placed together as illustrated in Fig. 4, and then two hollow rivets 22 are passed through the rivet openings, and the ends

thereof offset or riveted in position. One of said rivets also extends through the conductor terminal member 12 to firmly and permanently connect it electrically and mechanically with the adjacent terminal disk 16. The spark gap when thus assembled is permanently connected to the conductor wire at one end and the other end is detachably connected to a spark plug by having the screw-threaded upper end of the spark gap inserted through the hollow rivet 22, and the nut 23 on the spark plug is screwed down to hold the spark gap firmly in position thereon.

15 In the modified form illustrated in Figs. 2 and 3 I employ only two insulator members instead of three as in the form of the device before described.

In this form of the device the two insulating members are indicated by the reference numerals 24 and 25, laid one on top of the other and each provided with the counter-sunk opening clearly illustrated in Fig. 2, to receive the disk shaped terminals 16, 25 and the mica plate 26 is mounted on top of the member 25 and the parts are all assembled and held together by hollow rivets the same as in the other form, the upper plate 25 being provided with an opening 27 30 through which the spark may be observed.

The so-called insulating members are preferably made of fibrous or other hard rubber insulating material which is very inexpensive and which may be readily and easily 35 cut by dies to the forms shown in the drawings.

I preferably employ a sheet of mica as the means for observing the spark and at the same time protecting the space between 40 the spark terminals from dust and dirt and also from gas that might be exploded by the spark, although, obviously, any other material which will resist heat and at the same time be transparent may be employed.

45 Aside from the advantage of being inexpensively constructed, my device has several advantages over other devices of this kind, in that after the parts have been assembled the terminal disks cannot be moved from 50 their position and hence will always remain in their properly spaced position relative to each other.

Another advantage is that the spark gap is permanently attached to an electric con-

ducting wire and may be shipped and 55 handled easily without danger of breakage.

I claim as my invention:

1. An improved spark gap comprising a base member of insulating material, two disk-shaped metal terminal members on top 60 of the base member, a strip of transparent heat resisting insulating material on top of the disk-shaped terminals, and hollow rivets passed through the insulating members and the terminal members for firmly and permanently uniting them and for providing means whereby the spark gap thus formed may be electrically connected to a conductor wire and a spark plug.

2. An improved spark gap comprising a 70 base member of insulating material, two disk-shaped metallic terminals mounted on the base plate, a transparent insulating plate mounted on top of the terminals, a conductor wire having at one end a flat metallic 75 conductor mounted above one of the metallic disks, a hollow rivet passed through the said flattened conductor plate, the transparent insulating member, one of the disks and the base member, and another hollow rivet 80 passed through the other disk, and through the transparent insulating member and the base member, for the purposes stated.

3. An improved spark gap comprising a flat base member of insulating material having 85 two rivet openings therein, a second insulating member, having large circular openings therein, mounted on top of the base member, a third insulating member of transparent material, having rivet openings 90 therein, mounted on top of the second, a top insulating member on the transparent member, having rivet openings therein and a sight opening between the rivet openings, a conductor terminal having a rivet opening 95 therein, two disk-shaped metallic terminals mounted in the opening in the second insulating member, a hollow rivet extended through the base member, one of the disk members, the transparent insulator, the top 100 insulator and the said conductor plate, and a second hollow rivet passed through the base member, the remaining disk, the transparent insulator and the top member, substantially as and for the purposes stated. 105

Des Moines, Iowa, May 24, 1919.

OREN W. KINLEY.
